STRIPING FIXTURE

Frederick A. Benoit, Detroit, Mich., assignor to
Packard Motor Car Company, Detroit, Mich., a
corporation of Michigan

Application February 26, 1932, Serial No. 595,318

9 Claims. (Cl. 91—65)

This invention relates to guiding means for applying stripes and more particularly to guiding means for paint or lacquer applying instruments.

Paint and lacquer stripes were, for a long time, applied to automobile bodies, and similar objects requiring careful work, by means of a brush handled by skilled workmen. Such hand painting was found to be very expensive and not altogether uniform in the quantity of paint applied or the width of the stripe, and subsequently, stripe applying instruments were devised whereby a workman of more or less unskilled ability could applying a more satisfactory stripe and at a lower cost. Such instruments ordinarily incorporate some sort of a guide means, in the form of a wheel or an abutment, which is arranged to engage with a bead or a wall adjacent the line on which the stripe is to be made and such instruments have been satisfactory except in forming the junction of an angular type of stripe.

In the formation of angular stripes, considerable difficulty has been had with a guided instrument in making the junction so that the same will properly meet and at the same time not project beyond the intersection. The operator must be very careful in moving the instrument to an exact position and then raising it from the work adjacent the junction of such an angular stripe whereby consuming an undesired amount of time in applying the paint at the juncture of the stripe.

An object of this invention is to provide a new and novel form of guide for a paint or lacquer applying instrument in order that an angular stripe can be made rapidly and at the same time truly.

Another object of the invention is to provide means which can be readily applied in a window opening which will guide a striping instrument in its movement around an angular reveal so that the junction thereof can be quickly and accurately applied by an operator.

Still another object of the invention is to provide a guide for a striping instrument which is formed with means which will prevent the application of a stripe beyond the predetermined limit through automatically removing the dispensing element from the work.

Other objects of the invention will appear from the following description taken in connection with the drawing, which forms a part of this specification, and in which:

Fig. 1 is a plane view of the guide and a striping

instrument associated therewith in which two forms of corner guide means are disclosed;

Fig. 2 is a sectional view of the same;

Fig. 3 is a perspective view showing the preferred form of guide associated with the surface 60 to be striped;

Referring now to the drawing by the characters of reference, 10 indicates a surface to be striped by a paint or lacquer applying instrument. This instrument includes generally a handle portion 65, 12, body portion 13 having a guide roller 14 arranged at one side thereof, and an applicator nozzle 15 arranged on the same side of the body as the guide roller. The handle 12 also can serve as the paint or lacquer reservoir and within the body 13 is preferably arranged gear mechanism which is driven by the roller shaft for moving a stream of paint or lacquer through the applicator nozzle at a rate commensurate with the movement of the roller along a surface which will cause a uniform paint or lacquer stripe to be deposited from the nozzle upon the surface transversed thereby. The nozzle applicator is preferably hinged and a spring 16 is associated therewith to normally press the outlet end into contact with the surface transversed. The nozzle illustrated forms no part of this invention and is better illustrated and described in an application Serial No. 263,995, filed March 23, 1928, by John M. Christman. Any form of liquid dispensing device can be employed, however, as long as it incorporates a guide means and a fluid dispensing means.

When an angular stripe is to be applied, considerable difficulty has heretofore been encountered when using instruments of the character set forth due to the fact that the skill of the workman must be depended upon to terminate the stripes so that a finished junction will be formed, and it is the purpose of this invention to provide a fixture with which the striping instrument can be associated which will properly terminate the stripe ends without any delay in the operation.

The fixture illustrated includes a frame 17 having a pair of angularly disposed guides which are preferably in the form of runways, as indicated at 18. These runways are formed of U-shaped members which are welded or otherwise secured to the frame and are of a length such that the adjacent ends terminate short of their normal junction point. These fixed runways are preferably arranged adjacent the edge of the frame and the applicator roller is adapted to be rolled in the guideway so that the nozzle can be 110

drawn along the surface upon which the frame rests and preferably in a parallel relation to the edge of the frame.

In order that the angular stripe can be properly completed at its junction point, I provide movable guide means which can be associated with the adjacent ends of the tracks or guideway to selectively form a continuation thereof, and I have illustrated two different forms of mechanisms in this connection.

One of the mechanisms consists of a plate 20 having a track or guideway 21 formed in the upper surface thereof and a handle 22 fixed thereto for rotating the same upon a pintle 23 which is fixed to the frame. The guideway 21 is formed so that it can be aligned with either of the adjacent ends of the fixed guideway upon turning of the plate by means of the handle, and thus forms a guideway extension projecting preferably beyond the fixture frame so that the instrument roller can be guided therein and the paint deposited by the nozzle to the junction of the stripe to be formed. A stop member 35 is fixed to the outer face of the guideway 21 and has end portions projecting beyond each end thereof. Rotation of the plate 20 will be limited by the ends of the stop member engaging with the outer face of the adjacent fixed runways 18 whereupon the guideway 21 will be in alignment with one or the other of the adjacent fixed runways 18 depending upon the direction of rotation. It will thus be seen that the operator can quickly shift the member 20 so that an accurate angular stripe can be made.

The preferred form of guideway extension means consists of movable extension members 24 associated one with each of the adjacent ends of the fixed angularly disposed guide members. A U-shaped bracket 25 is fixed to the frame at the adjacent ends of the fixed runways, forming substantially a continuation thereof, and the guide extension members 24 are fixed to pintles 26 which are pivotally mounted at one end of the brackets 25. A coil spring 27 is associated with each of the pintles and the associated bracket to frictionally retain the guide extensions in any position in which they are moved. The guide extensions project beyond the junction of the stripe to be made and as they form a continuation of the fixed guide members, the implement is thus guided so that the nozzle will form an angular stripe beyond the junction point.

In order to prevent the nozzle from engaging the surface to be striped beyond the junction point as the implement is rolled along the guideway, I provide abutment members 28 which are fixed to the under side of the free ends of the guide extensions by screws 29 or any other suitable means. These extensions 30 project into the plane of the nozzle movement while guided in the extensions and are provided with a beveled edge upon which the nozzle will ride and be raised above the surface being striped. Such a beveled edge is arranged so that the stripe made by the nozzle will be discontinued exactly at the junction point of the stripe made or to be made by the nozzle when drawn along the adjacent angularly disposed guideway means. These abutment members permit the operator to move the instrument at a uniform speed and without any particular hesitation in seeking to terminate the stripe at the proper point such as has been heretofore necessary. As the two guide extensions 24 extend beyond the end of the frame, it is necessary that one must be raised when the other is

to be moved to form a continuation of its associated fixed guideway but this manipulation of the extensions requires very little time.

The frame, if desired, can be formed to fit within any depression so that a stripe can be formed a uniform width away from the edge of the depression. As an example of this, the frame can be formed to fit into a window so that the instrument can be guided around the reveal. Angular stripes can quickly and accurately be made on a plane or raised surface without any hesitancy by the operator in forming the junction of the stripe and with absolute accuracy.

Although the invention has been described in connection with a specific embodiment, the principles involved are susceptible of numerous other applications which will readily occur to persons skilled in the art. The invention is therefore to be limited only as indicated by the scope of the appended claims.

What I claim is:

1. In a guideway structure for striping instruments of the type having a dispensing nozzle adapted to be moved along a surface to be finished, a frame, angularly disposed runways fixed on the frame and terminating short of their normal junction point, and a member pivoted to the frame, said members having a runway adapted to form a continuation of either of the fixed runways upon pivotal adjustment thereof.

2. In a fixture for guiding striping instruments, a frame, a pair of angularly disposed guide members fixed on the frame, said guide members terminating short of their normal junction, guide extensions pivotally mounted on the frame and adapted to be moved into position forming continuations of the adjacent ends of the guide members, and means normally maintaining the extensions in any position into which they are moved.

3. In a fixture for guiding striping instruments of the type in which a dispensing nozzle is moved along a surface to be finished, a frame, a pair of angularly disposed guide members fixed on the frame, said members being engaged by the instrument in forming an angular stripe and terminating short of their junction, movable guide extensions adapted to be moved into position forming a continuation of the adjacent ends of the guide members, and abutment means on said extensions projecting into a plane to terminate the stripe application of the nozzle, said abutment means being arranged at the junction of the angularly disposed stripes being made.

4. In a fixture for guiding striping instruments of the type in which a dispensing nozzle is moved along a surface to be finished, a frame, a pair of runways fixed on the frame and extending in an angular relation, said runways being short of their normal junction, runway extensions pivotally mounted on the frame and movable into a position forming a continuation of the adjacent ends of the fixed runways, and abutment members fixed to the extensions and projecting therefrom into the path of the instrument nozzle guided by the extensions, said abutments being associated to lift the nozzle at the point of junction between stripes applied while the instrument is being guided by the fixture.

5. In a fixture for guiding a striping instrument of the type in which a dispensing nozzle is moved along a surface to be finished, a frame, a pair of angularly disposed guide members fixed on the frame, said members being engaged by the instrument in forming an angular stripe and

- terminating short of their junction, pivoted 5
guide means on the frame adapted to be moved
into a position forming a continuation of either
adjacent end of the fixed guide members and
abutment means on said pivoted guide means
projecting into the path of the nozzle movement
to terminate the stripe application on the
surface, said abutment means being arranged to
form the junction of the angularly disposed
10 stripe being made by the instrument.
6. In a fixture for guiding a striping instru-
ment of the type in which a dispensing nozzle
is moved along a surface to be finished, a frame,
a pair of angularly disposed guide members fixed
15 on the frame, said members being engaged by
the instrument in forming an angular stripe and
terminating short of their junction, movable
guide means on the frame adapted to be moved
into a position forming a continuation of either
20 adjacent end of the fixed guide members, and
abutment means on said movable guide means
projecting into the path of the nozzle movement
to terminate the stripe application on the
surface, said abutment means being arranged to
25 form the junction of the angularly disposed
stripe being made by the instrument.
7. In a fixture for guiding striping instru-
ments of the type in which a dispensing nozzle
is moved along a surface to be finished, a frame,
30 a pair of angularly disposed guide members fixed
on the frame, said guide members being engaged
by the instrument in forming an angular stripe and
terminating short of their junction, movable
guide extensions adapted to be adjusted to
35 form a continuation of the adjacent ends of the
guide members, means associated with said guide
extensions for maintaining them in any position
of adjustment, and abutment means on said ex-
tensions projecting into the path of the nozzle
movement to terminate the stripe application
on the surface, said abutment means being ar-
ranged at the junction of the angular stripe be-
ing made. 80
8. In a fixture for guiding striping instru-
ments of the type in which a dispensing nozzle
is moved along a surface to be finished, a frame,
a pair of angularly disposed guide members fixed
85 on the frame, said guide members being engaged
by the instrument in forming an angular stripe and
terminating short of their junction, movable
guide extensions adapted to be adjusted to
form a continuation of the adjacent ends of the
90 guide members, springs associated with said guide
extensions for maintaining them in any position
of adjustment; and abutment means on said ex-
tensions projecting into the path of the nozzle
movement to terminate the stripe application,
95 said abutment means being arranged at the junc-
tion of the angular stripe being made.
9. In a guideway structure for striping instru-
ments of the type having a dispensing nozzle
adapted to be moved along a surface to be fin- 100
ished, a frame, angularly disposed guide mem-
bers fixed on the frame and terminating short
of their junction point, a member pivoted to the
frame, said member having a guide adapted to
form a continuation of either one of the fixed 105
guide members upon pivotal adjustment thereof,
and stop means on said pivoted member arranged
to engage with said fixed guide members when the
guide portion of the pivoted member is in align-
ment therewith. 110

CERTIFICATE OF CORRECTION.

Patent No. 1,971,898.

August 28, 1934.

FREDERICK A. BENOIT.

It is hereby certified that error appears in the printed specification of the above numbered patent requiring correction as follows: Page 1, line 14, for "applying" read apply; and page 3, line 95, claim 8, after "application" and before the comma, insert the words on the surface; and that the said Letters Patent should be read with this correction therein that the same may conform to the record of the case in the Patent Office.

Signed and sealed this 25th day of June, A. D. 1935.

(Seal)

Bryan M. Battey
Acting Commissioner of Patents.
